DOOR CHECK AND CLOSER

Frederick Albert Masson, Winnipeg, Manitoba,
Canada

Application September 12, 1946, Serial No. 696,389

1 Claim. (Cl. 16—49)

1 The majority of door checks, at present on the market, are of the oil type and permit the door to swing open quickly. On the return movement of the door the speed of closing can be regulated either fast or slow. The operation is accomplished by compressing a spring on the door opening movement and this spring returns the door while the return speed is governed by the movement of oil under pressure of the spring.

The above mentioned door checks, when new and properly adjusted, work well, but in time, the working parts wear and the oil depreciates depositing heavy scum with the result that the checks are continually requiring adjustment or repairs.

The principal object of the present invention is to provide a mechanically operated check, thus eliminating the oil, and to construct the various parts principally of stampings so that they can be readily produced and assembled in quantity production at low cost and can be quickly repaired or replaced.

A further object of the invention is to construct the device so that it may be used for either right or left handed doors or it may be used on the door or on the door framework.

A further object of the invention is to provide regulating means for the closing speed of the door and said means adjustable for varying weights of doors.

A further object of the invention is to provide means to increase the power of the check to operate the latch of the door and insure the final closing.

A further object of the invention is to provide a silently operable check so that it can be used in hospitals or places where quietness is essential.

A further object of the invention is to design the construction of the door check for quick insertion or removal of the spring and said spring inserted as a unit with built up pressure for ample power operation of the device and without the necessity of a covering spring barrel.

A still further object of the invention is to enclose the mechanical parts within a dust proof casing and with a removable cover so that the working parts can be exposed for adjustment, cleaning or replacement while on the door.

With the above important and other minor objects in view which will become more apparent as the description proceeds, the invention consists essentially in the construction and arrangement of parts hereinafter more particularly described, reference being had to the accompanying drawings in which:

2 Figure 1 is a perspective view of the upper corner of a door frame and door showing the check in position.

Figure 2 is an enlarged horizontal sectional view taken on the line 2—2, Figure 1.

Figure 3 is a vertical sectional view taken on the line 3—3, Figure 2.

Figure 4 is a horizontal sectional view taken on the line 4—4, Figure 3.

Figure 5 is a vertical sectional view taken on the line 5—5, Figure 2.

In the drawings like characters of reference indicate corresponding parts in the several figures.

15 A door framework 1 encloses a door 2 hinged at 3 to the framework. The invention, now to be described, is located on the upper right hand side of the door.

An angle shaped plate has the vertical portion 20 4 thereof fastened to the door by screws 5 at each end. The horizontal portion 6 is of an irregular shape as shown by the outline in Figures 2 and 4 and the edges thereof are turned up as indicated at 7. The angle shaped plate is designed to be punched out and shaped in one operation.

A cover member 8 of sheet metal is bent in a Z shape as shown in Figure 3. The upper edge 9 is received against the upper face of the plate 4 and is fastened thereto by screws 10. The sides 30 11 of the member 8 conform to the shape of the plate 6 so that the lower edges thereof are received against the upward extension 7 and are fastened thereto by screws 12. This cover member is adapted to be pressed in one operation. The member 8 and the angle shaped plate form a dust proof casing.

The check mechanism is carried by a framework comprising two horizontal plates 13 and 14. These plates are punched from flat metal and are 40 spaced from each other and connected by three posts 15 and a pair of rectangular shaped standards 16. One of the standards has a central extension 16' for a purpose later explained.

The upper plate 13 is fastened to the posts and standards by screws 17. The plate 14, is fastened to the standards by screws 18 while the posts pass through the plate 14 and nuts 19 hold the plate against shoulders on the posts. The lower extending ends of the posts then pass through holes 50 in the plate 6 and nuts 20 are screwed on thereunder to hold the framework rigid with the check casing.

A shaft 21 passes through the casing and the framework and where it passes through the 55 framework a reinforcing plate 22 is spot welded

to the plates 13 and 14 to provide a wider bearing for the shaft. Both ends of the shaft are squared and slightly down from the center, a stud 23 is carried by the shaft to hook on to the center end of a spiral flat spring 24. This spring is sold by the manufacturer in a tightly wound condition with an annular heavy wire 25 there-around. The ends of this heavy wire are slightly spaced as at 23. The spring and wire are inserted complete within the check, are held in position by the posts 15, while the space 26 receives the extension 16', previously mentioned.

A flat worm wheel 27 is slidably received on the shaft 21, overlies the coil spring, and the upper face carries a pawl 28 which is pivotally fastened to the worm gear at 29. A ratchet 30 is fastened to the shaft 21 by a pin 31, overlies the worm gear, and the teeth are adapted to receive the pawl 28. A plate 32 is slidably received on the shaft 21, above the ratchet, and is provided with an arm 33 having a slot 34 which receives a pin 35 extending upward from the pawl 28. A coil spring 36 encircles the shaft 21 and is positioned between the plate 13 and the plate 32 to hold the latter plate firmly against the ratchet 30.

A horizontal shaft 37 is supported in bearings 38 from the standards 16, suitable screws 39 being provided in the standards to hold the bearings firmly. This shaft has a small portion cut with worm threads so that it meshes with the worm wheel 27. Sleeves 40 are carried by the shaft 37, one being fixed to said shaft and the other carrying a disc 42 and slidable on said shaft. Strap-shaped springs, centrally provided with semi-cylindrical weights 41, have the ends thereof secured to said sleeves 40 in equi-spaced relation therearound so that, when the shaft 37 is rotated, the weights will move outwardly under centrifugal force and draw the disc inwardly along the shaft toward the opposite sleeve. A Z-shaped lever 43 is pivotally mounted on the plate 14 below the shaft 37 and the upper end of this lever is provided with a small leather face which is positioned to contact the face of the disc 42. In the rotation of the shaft 37 the disc 42 is moved towards the leather and when in contact the friction of same against the disc face regulates the speed of the shaft 37 and so forms a governor. A winged screw 44 screws through the bottom of the casing, passes through a hole in the plate 14 and the end contacts the opposite end of the Z-shaped lever 43. When this winged screw is screwed up, the leather moves closer towards the disc 42, and when the winged screw is screwed down, a spring 45 moves the leather away from the disc 42 so that the winged screw 44 can regulate or vary the set speed of the shaft 37. Once the speed is set, a lock nut 46, carried by the winged screw can be tightened against the lower part of the casing.

The upper end of the shaft 21, above the casing, receives a washer 47 and then a split arm 48 which is locked to the square end of the shaft by a bolt 49 passing across the split arm. The opposite end of the arm is pivoted at 50 to an adjustable arm 51 and this arm is pivoted to a bracket 52 carried by the upper part of the door frame. Before these arms are connected, the shaft 21 is turned by a wrench or other suitable tool to wind a number of coils of the spring thereon. The arms are then attached.

In operation, when the door is opened, the movement produces a clockwise movement of the arm 48 which increases the pressure on the spring 24. At this time it might be mentioned that the outer end of the spring is frictionally held by the

heavy wire 25. In this movement the shaft 21 turns and also the ratchet wheel 30. As the spring 36 is pressing the plate 32 against the ratchet wheel, this plate also turns and accordingly, the pin 35 moves outward in the slot 34 and releases the pawl 28 from the ratchet. When the pin 35 reaches the end of the slot the plate 32 stops while the shaft 21 continues to turn. This prevents the "click" which would be caused by the pawl passing over the ratchet teeth. When the manual pressure is released from the door, the built up pressure in the spring 24 turns the shaft 21 in the opposite direction. Accordingly the ratchet in turning with this shaft turns the plate 32 and the pin 35 returns down the slot 34 and engages the pawl 28 with the ratchet wheel 30. The power is then transmitted from the spring to the work gear 27 and this, in turn, operates the governor shaft 37 at the speed set by the winged screw 44. By this arrangement the door starts to shut at the speed set by the governor. When the door is at the position of closure the resistance of the latch (not shown) has a tendency to stop further movement of the door. At this time the momentum of the governor continues the rotation thereof and this relieves the spring from the work of driving same. Accordingly all the power of the spring is turning the shaft 21 and as the levers 43 and 51 are approaching their dead-center position this power is increased several times and concentrated against the door to operate the latch and positively shut the door.

As all flat portions of this check are made from sheet metal, stamped into shape and the holes punched, the device readily lends itself to cheap quantity production. Further, by carefully designing all the various parts, they readily slip together without requiring special tools and accordingly, the assembling of same is speedy. The spring, when bought from the manufacturer is tightly wound and encircled by the heavy wire for shipping convenience. No change is made to this arrangement and it is easily slipped into position. The heavy wire takes the place of the usual casing for the spring and at the same time, due to the spring being tightly wound, more power is transmitted to the shaft 21 with only a few turns instead of a large number of turns as would be required if the spring was loose in a container. Should any of the parts wear and cause trouble, the casing construction permits the cover to be removed and the working parts are all exposed for repairs while the device is on the door. If replacements are required, the various parts are very cheaply made and accordingly will not be costly. If a door having an opposite swing is to be controlled, the check is simply turned upside down and the arm 48 connected to the opposite end of the shaft 21. The only difference in the operation will be that the adjustment of the governor is on the top instead of at the bottom. The check may be fastened to the door frame in a similar manner if required. As the shaft 21 only moves through an arc of about 90° very little oil for lubrication is required by the various parts and accordingly, the check will not be discolored by leaking oil or grease as so often occurs in the oil operated checks and the check itself will last indefinitely. If the door is light, only a few coils of the spring are required on the shaft 21. If the door is heavy, the shaft 21 is just wound a little tighter before the arm 48 is attached. Should it be necessary to hold the door open, it would be a simple matter to swing the door to the position required, release the lock nut 46 and then screw up the winged bolt 44. This will lock the

governor and the spring will be unable to operate the mechanism.

What I claim as my invention is:

In a door check: a casing adapted to be secured to a door and including a removable cover; an open framework supported by said casing; a shaft passing through said above assembly and carried by said framework; a spring connected to and adapted to drive said shaft when said door is released after being manually opened and be 10 tightened when said door is opened; a ratchet supported by said framework and driven by said shaft; a governor rotatably mounted in said framework; driving means for driving said governor, said driving means including a pawl normally engaging said ratchet whereby said governor will be driven from said ratchet; a primary lever connected to said shaft; a secondary lever pivotally connected to said primary lever and adapted to be secured to a frame for said door; means frictionally operable by the movement of said ratchet for moving said pawl out of engage- 15

ment with said ratchet, in the spring tightening movement of said shaft, and for re-connecting said pawl with said ratchet in the reverse movement of said shaft.
